F. D. HOFFMAN

PUMP

Filed Oct. 10. 1923

UNITED STATES PATENT OFFICE.

FRED D. HOFFMAN, OF KANSAS CITY, MISSOURI.

PUMP.

Application filed October 10, 1923. Serial No. 667,646.

To all whom it may concern:

Be it known that I, FRED D. HOFFMAN, a citizen of the United States, residing at Kansas City, in the county of Jackson and State 5 of Missouri, have invented certain new and useful Improvements in Pumps; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

15 This invention relates to pumps and the primary object of the invention is to provide a well pump which is so constructed that water may be raised at a greater depth than is possible with the ordinary lift pump. 20 The result is accomplished by providing a pair of connecting cylinders with pistons therein having alternating suction and compression stroke, that is when one piston is moving on its suction stroke the other is moving on its compression stroke and vice versa, the pistons becoming alternately force and suction pistons, the water being delivered on the suction side of the pump, there being certain valve mechanism cooperating with the 25 pistons to produce the desired result. The novel construction of the invention will be apparent by reference to the following description in connection with the accompanying drawings, in which—

30 Fig. 1 is a vertical longitudinal sectional view through a pump constructed in accordance with my invention.

35 Fig. 2 is a cross sectional view at the center line of the pump, one of its barrels 40 being shown in elevation.

Fig. 3 is a cross sectional view through one of the pump barrels showing the flap valve co-operating therewith.

Referring now to the drawings by numerals of reference, 1 and 2 designates the two cylinders of the pump having depending tubes or barrels 3 and 4 connected at their lower ends by semi-cylindrical chamber 5 divided into an inner compartment 6 and an 45 outer compartment 7. The barrels 3 and 4 and the chamber 5 provide a U-shaped structure. The compartments 6 and 7 communicate with the barrels 3 and 4 at their upper ends, the partition 8 dividing them, extending across the lower ends of the barrels to provide the compartment 7 at all times in

communication with the barrels and the compartment 6 which alternately and intermittently communicates with the respective barrels dependent upon the stroke movements 50 of the pistons 9 and 10 in the cylinders 1 and 2. The upper ends of the partition 8 carries flap valves 11 and 12 which are adapted to swing inwardly to closing positions and contact with the stops 13 and 14, the outward 55 swinging movement of the valves however is limited by the fingers 15 and 16 which may contact with the top plate 17 of the compartment 6. The top plate 17 is provided with the valve seat 18 having a spider 19 60 therein through which may reciprocate a valve stem 20 having on its lower end an inwardly opening valve 22 adapted to seat on the seat 18. The stem 20 extends above the ground or through a platform 23 and is connected to a pivoted lever 24 having an adjustable counter-balanced weight 25 at one end. The pistons 9 and 10 are shown as connected to a pivoted lever or walking beam 26 65 by the connecting rods 27 and 28. The walking beam 26 is supported on a shaft 26' which may be rocked by appropriate mechanism. If the parts are assembled as shown and the piston 10 moves on its downward stroke, the piston 9 will move on its out stroke so pressure will be exerted upon the liquid in the column or barrel 4 closing the valve 12 and forcing the liquid through the compartment or passageway 7 and into the column or barrel 3. The momentum of the forced liquid 70 will cause the valve 11 to unseat and permit water to be drawn from the compartment 6, the suction thereby created unseating the valve 22 to allow water or liquid in which the chamber 5 is submerged to flow into the 75 column or barrel 3 so that it can be drawn into the cylinder 1 and escape through the discharge port 29. When the piston 9 descends and the piston 10 moves on its suction 80 stroke the valve 11 will close and the valve 12 will open so that liquid will be forced from the column or barrel 3 through the compartment 7 into the barrel or column 4. The valve 12 at this time being unseated so that liquid can be drawn from compartment 6 85 creating a suction therein to unseat the valve 22. The passageway or compartment 7 is constructed with respect to the cross sectional areas of the barrels 3 and 4 so that following the rate of flow, it is obvious that the water will pass through the passageway 90 7 at a high velocity exerting an injector ac-

tion on the water in compartment 6, due to the fact that it travels at a relatively high rate. When the water is elevated into the cylinder 2 it may escape into the discharge opening or nozzle 30. The weight 25 can be set so as to slightly over-balance the valve 22, therefore when the pump is operated the suction created in compartment 6 will maintain the valve unseated, but when the pump stops the slight preponderance of weight of the adjustable weight 5 will cause the valve 22 to close.

It is understood of course that before the pump is first started it must first be primed because the discharge openings 29 and 30 are above the water level and it should also be apparent that if the valve 22 remains unseated when the pistons were at rest the water in the cylinders and barrels would seek the level of the water in which the lower part of the pump was submerged and would spill out through the openings uncovered by either the valve 11 or 12 which happened to be unseated and then flow through the opening surrounded by the valve seat 18 but if the valve 22 is closed or seated there can be no escape of the water in barrels 3 and 4. When the pump stops operating the operator can press down on the free end of the lever 24 and manually close the valve 24 but if the weight 25 is properly adjusted for slightly over-balancing valve 22, it will be apparent that when the pump stops and the suction ceases in compartment 6 the valve 22 will move on its seat and automatically close the opening surrounded by the seat 18. Therefore the water will be held in the pump so it will not be necessary to re-prime it when it is next operated. If the weight 25 is properly positioned on the lever arm 24, it will constitute a tell-tale for the pump, that is with proper adjustment of the weight 25, each time the valve 11 or 12 opens to permit water to enter the columns or barrels 3 or 4, a slight opening impulse will be given to the valve 22 and this movement will be communicated to the lever arm 24 so the lever arm 24 will vibrate, so the operator at the top of the well will be apprised of the fact that the pump is properly functioning.

It will be apparent from the foregoing that a pump constructed in accordance with my invention is a combined lift and force pump and that the pistons are solid pistons properly packed, so there will be no leakage of water past them and so that no air can enter the water columns or barrels, except through the discharge openings 29 and 30 when the pistons are in their up positions.

An important feature of my invention is the action of the water in the U-tube construction of my pump. Assuming that power is applied to the beam 26 the piston

10 starts on its up stroke thus creating suction upon the column of liquid in the cylinder 2 resulting in the suction opening the flap valve 12 and drawing liquid through the veriture tube from the compartment 6 in addition to that coming through compartment 7, the piston 9 passes below the discharge opening 29 and thus applies a downward force to the column of liquid in the cylinder 3, this column having started on its downward course of its own accord, due to its loss of upward momentum and the action of gravity, so that the flap valve 11 is closed and the downward column of liquid compelled to pass through the compartment 7 to the cylinder 4 for the purpose of boosting the column of liquid 4 after the suction stroke of the piston 10 has been released by passing the point of discharge 30, such piston traveling through and remaining in its up position a sufficient length of time for the column of liquid to spend its momentum through the discharge opening 30, the object being to allow the natural forces of gravity and the momentum stored in the column of liquid to entirely expend themselves, thus at no time attempting to resist the action of momentum as is the case in most pumps, resulting in my pump being of a higher efficiency than pumps of the conventional type.

In order to better illustrate the advantage gained by this construction, attention is called to the fact that it became necessary to install baffle plates in locomotive tenders in order to prevent the momentum stored in the water due to the side sway of the tender from overturning the same and I desire to utilize this power rather than work against it.

What I claim and desire to secure by Letters-Patent is:

1. A pump comprising two cylinders having inlets and outlets, a U-shaped connection between them, the U-shaped connection having inwardly opening valves in the walls thereof, pistons in the cylinders and means for simultaneously operating said pistons in opposite directions.

2. A pump comprising two cylinders having inlets and outlets, a U-shaped connection between them having inwardly opening valves in the wall thereof, a valved chamber communicating with the U-shaped connection when the inwardly opening valves are unseated, pistons in the cylinders and means for simultaneously operating said pistons in alternating opposite directions so that one piston functions as a compression piston when the other is functioning as a suction piston.

3. A pump comprising two cylinders having inlets and outlets, a U-shaped connection between them having inwardly opening valves in the wall thereof, a valved

chamber communicating with the U-shaped connection when the inwardly opening valves are unseated, pistons in the cylinders and means for simultaneously operating 5 said pistons in alternating opposite directions so that one piston functions as a compression piston when the other is functioning as a suction piston, the pistons having movement to alternately cover and uncover 10 the outlets.

4. A pump comprising two cylinders having outlets in the walls thereof, reciprocating pistons in the cylinders having movements to cover and uncover the outlets, 15 hollow columns connected to the cylinders, a semi-cylindrical chambered member connecting the lower ends of the column and divided into two compartments, one of 20 which is in constant communication with both columns and the other of which is in alternating communication with the respective columns the second mentioned compartment having a valve seat, a valve receivable on said seat having a stem, a lever 25 connected to the stem and a counter-balancing weight on the lever.

5. A pump comprising two cylinders having outlets in the walls thereof, a tubular member connected to the ends of the cylinders, a chamber connected to the ends of the tubular members and having a partition to provide a passageway communicating with the ends of the cylinders, the passageway having a restricted port area, the wall on 30 one side of the partition having a valved port, the valve having inwardly opening movement and inwardly opening valves communicating the chamber with the tubular members and oppositely moving pistons in the 35 cylinders.

6. A pump comprising two cylinders having outlets in the walls thereof, a tubular member connected to the ends of the cylinders, a chamber connected to the ends of the 40 tubular members and having a partition to provide a passageway communicating with the ends of the cylinders, the passageway having a restricted port area, the wall on one side of the partition having a valved 45 port, the valve having inwardly opening movement and inwardly opening flap valves communicating the chamber with the tubular members and oppositely moving pistons in the cylinders.

55 7. A pump comprising two cylinders having outlets in the walls thereof, a tubular member connected to the ends of the cylinders, a chamber connected to the ends of the tubular members and having a partition to 60 provide a passageway communicating with the ends of the cylinders, the passageway having a restricted port area, the wall on one side of the partition having a valved 65 port, the valve having inwardly opening movement and inwardly opening flap valves

communicating the chamber with the tubular members, said valves having fingers to contact with the part of the pump structure to limit the opening movement of the flap valves and oppositely moving pistons in the 70 cylinders.

8. A pump comprising two cylinders, having inlets and outlets, oppositely moving pistons in said cylinder, a tubular member connected to the inlets of said cylinders, a 75 U-shaped member providing a passageway communicating with the ends of the tubular members, the passageway having an effective cross section less than the cross sections of the tubular members so that liquid 80 passing from one tubular member to the other through the passageway will flow at increased velocity through the passageway and inwardly opening valves in the tubular members above the passageway. 85

9. A pump comprising two cylinders, having inlets and outlets, oppositely moving pistons in said cylinder, a tubular member connected to the inlets of said cylinders, a U-shaped member providing a passageway 90 communicating with the ends of the tubular members, the passageway having an effective cross section less than the cross sections of the tubular members so that liquid passing from one tubular member to the other through the passageway will flow at increased velocity through the passageway and inwardly opening valves in the tubular members above the passageway, a chamber above the passageway 95 communicating with the tubular member through openings controlled by the inwardly opening valves and an inwardly valve in the chamber. 100

10. A pump comprising two cylinders, pistons for the cylinders, and means for simultaneously actuating said pistons in alternating opposite directions, apertures in the side of the cylinders for the discharge of the liquid, a bowl at the base of and connecting the cylinders, a semi-circular partition in such bowl, forming a confined passageway and communicating with the bottoms of each of said cylinders, and valves at the bottoms of each cylinder but having 105 no relation with the confined passage-way. 110

11. A pump comprising two cylinders, pistons for the cylinders, and means for simultaneously actuating said pistons in alternating opposite directions, apertures in the side of the cylinders for the discharge of the liquid, a bowl at the base of and connecting the cylinders, a semi-circular partition in such bowl forming a confined passage-way and communicating with the bottoms of each of said cylinders, valves at the bottoms of each cylinder but having no relation with the confined passage-way and a valve in the bowl for permitting liquid to enter when the pistons are actuating. 115 120

12. A pump comprising two cylinders, 125 130

pistons for the cylinders, and means for simultaneously actuating said pistons in alternating opposite directions, apertures in the side of the cylinder for the discharge of the liquid, a bowl at the base of and connecting the cylinders, a semi-circular partition in such bowl forming a confined passageway and communicating with the bottoms of

each of said cylinders, valves at the bottoms of each cylinder but having no relation with the confined passageway, a valve in the bowl for permitting liquid to enter when the pistons are actuating and means for closing the last named valve.

In testimony whereof I affix my signature.

FRED D. HOFFMAN.
